UNITED STATES PATENT OFFICE.

CHARLES L. BURDICK, OF MADISON, WISCONSIN.

PAINT-DISTRIBUTER.

SPECIFICATION forming part of Letters Patent No. 434,105, dated August 12, 1890.

Application filed November 15, 1889. Serial No. 330,404. (No model.)

To all whom it may concern:

Be it known that I, CHARLES L. BURDICK, of Madison, in the county of Dane and State of Wisconsin, have invented certain new and useful Improvements in Paint-Distributors; and I do hereby declare that the following is a full, clear, and exact description thereof, reference being had to the accompanying drawings, and to the letters of reference marked to thereon, which form a part of this specification.

This invention relates to a novel construction in paint-distributors, and more particularly to that class of such devices known as "air-brushes" which are adapted for use in painting and shading pictures.

The invention consists in the details of construction and combination of parts herein-after fully described, and pointed out in the appended claims.

20 In the accompanying drawings, Figure 1 is a view in side elevation of a device constructed in accordance with my invention. Fig. 2 is a plan view of the same with the cover removed to show the interior construction.

25 Fig. 3 is a detail view of the removable cover. Fig. 4 is a view of the apparatus in central longitudinal section taken on the line 4 4 of Fig. 7. Fig. 5 is a longitudinal sectional view taken on the indirect line 5 5 of Fig. 2. Fig.

30 6 is a longitudinal sectional view taken on the indirect line 6 6 of Fig. 2. Fig. 7 is an end view of the apparatus. Fig. 8 is a fragmentary sectional view of the paint-receptacle, showing the paint conductor or nibs in cross-section.

35 In said drawings, A indicates the case of the instrument, which is closed at its ends by heads or plates a a'. The said case is also divided into two compartments a² a³ by a par-

40 tition or diaphragm a⁴, conveniently located about midway the ends thereof. A part of the case adjacent to the compartment a³ is cut away, as shown, and said part is provided with a removable cover A', having suitable devices

45 for securing the same in position, (herein shown as comprising a flange a⁵), located at the end and adapted to engage the under side of the case, and a sliding pin or lug a⁶, having a handle projecting through a slot in the case.

50 The said cover is provided, also, with a slot a⁷, herein referred to. The compartment a² is made air-tight, and is provided at its rear

end with a short pipe or tube A⁸, which has screw-threaded connection with an aperture in the head a of the casing. The tube A⁸ 55 communicates with the hose or pipe leading from the apparatus employed for forcing the air. Within an aperture formed in the diaphragm a⁴ a nipple b is secured, preferably by a screw-threaded joint. Said nipple b extends into the compartment a³, and is provided with an enlarged or bulging end portion having an aperture or perforation b' at one side thereof for the escape of the air.

B indicates a pipe or tube section located 6: within the forward end of the compartment a³ and provided at its forward end with a nozzle b², which projects through a slot a⁹ in the head a'. The said tube B communicates with the nipple b by means of a short flexible 70 tube or hose b³, which embraces and is secured to the adjacent ends of said tube B and said nipple. The flexible tube b³ is preferably made of rubber, so as to permit the tube B to move freely with relation to the nipple, 75 said flexible tube being secured to said nipple by means of strands of wire or other suitable material, which is wound around the flexible tube in the rear of the perforation b². The tube B is secured to the case by means 8c of a clip or block b⁴, to which said tube is rigidly secured, said block being secured by means of a headed screw b⁵, which passes through a slot a⁹ in the case and enters a screw-threaded opening in said clip. The 85 said clip is conveniently secured to the tube B near the rear end of the latter, and it follows from the construction above described that by loosening the screw b⁵ said tube B can be moved longitudinally and then secured in 90 its adjusted position by tightening the screw.

A⁴ indicates a set-screw passing through a screw-threaded perforation in the case adjacent to the pipe B and having its inner end adapted to bear against the outer or free end 95 of said pipe, so that by turning said screw A⁴ the said pipe B can be moved transversely to the case, it having sufficient flexibility to permit such movement.

C indicates the paint receptacle or holder 100 secured at an angle to the forward end of the case. The said paint-receptacle is formed with an open dish-shaped body portion c and a flat end or head c', and the paint is intro-

duced therein by pouring or otherwise. The said head or plate c' is formed at about its center with a small perforation c^2 , through which the paint can escape.

5 c^3 c^3 indicate two small pointed plates or nibs located above and below the perforation c^2 , between which the paint is conducted from the holder C. The said nibs are arranged very closely together, so that only a little 10 space is left between them. The said nibs are so located that the space between them is in alignment with the orifice in the nozzle, so that when the said nozzle is moved transversely by the screw A⁴ it will always be in 15 alignment with the said space between the nibs. It follows from this construction that when an air-blast passes from the nozzle b^2 and is projected into the space between the nibs any paint that may be between said nibs will 20 be carried forward in the form of a fine spray under the influence of said air-blast. The adjustment of the nozzle b^2 longitudinally and transversely allows a greater distribution of the paint and also a greater quantity of 25 paint to be acted upon by the air-blast; but these adjustments are in a manner permanent and cannot be made during operation, but it is necessary to stop the work which is being done to make the same.

30 To provide means whereby light and heavy lines can be made with this instrument during the progress of the work, I construct the nibs c^3 c^3 so that they can be brought together or separated, and thus permit a greater quantity of paint to be acted upon by the air-blast. To accomplish this object, the plate or disk forming the head c' of the paint-holder is made of relatively thin material possessing a certain degree of flexibility, so that the 35 same can be pressed inwardly, and after the pressure is removed the same will resume its normal position. The nibs being secured directly to said plate c' , it is evident that when the said plate is pressed inwardly the 40 said nibs will be brought together, thereby lessening the space between them and affording a smaller passage for the paint. The means for securing this pressure upon the plate c' comprises a lever D, pivoted within 45 the case and having its short arm d projecting outside through a slot made in the head a' and resting normally in contact with the head c' . The said lever D is preferably pivoted between two lugs d' d' , formed upon an 50 arm or bracket D', which is secured within the forward end of the case. The said arm D' passes rearwardly and parallel with the sides of the case to a point about midway of the ends of the compartment a^3 , whereupon 55 it is deflected and secured to the side of the case, preferably by means of a screw. The long arm d^2 of the lever D extends rearwardly to the face of the bracket D' and has its edge which is adjacent thereto inclined, so that it 60 is thinner at its rear end.

65 E represents a thumb piece or lever pivoted at its lower end to a suitable bar E',

hereinafter to be referred to, and extending upwardly between the inclined edge of the arm d^2 of the lever and the adjacent face of 70 the bracket D'. The said thumb-piece E is adapted to swing forwardly and backwardly on its pivot, so that as the same engages the inclined edge of the arm d^2 it will serve to gradually swing the same outwardly in an 75 obvious manner, and thereby press the short arm d against the head c' of the paint-holder. A set-screw d^3 is arranged in one of two lugs d^4 d^4 , formed upon the plate in the rear of the lugs d' . The head of said set-screw d^3 is arranged for contact with the swinging thumb-piece E when the same moves forwardly, so that its forward movement can be limited to thereby limit the extent to which the plate c' of the paint-holder will be pressed inwardly 80 to control the flow of paint to the nibs. The said lugs d^4 d^4 are arranged one above and one below the long arm of the lever D, although the same do not come in contact therewith, but extend outwardly to a point adjacent to the pipe B. The said lugs d^4 are arranged a sufficient distance apart to permit the said pipe B to pass between the same when said pipe is moved transversely by the screw A⁴, and thus serve to guide said pipe, 85 so that the nozzle b^2 will always be in alignment with the space between the nibs c^3 .

90 The operating-lever E extends upwardly through the slot a' in the removable cover A' of the case, and is provided at its upper end with a suitable head or enlargement, whereby it may be operated. The head of said operating-lever is located so that it will be adjacent to one of the fingers when the instrument is held in the hand in being used, and thus the same can be easily and quickly manipulated. It will thus be obvious that by pressing the said lever forward or backward the nibs can be brought together or separated, as desired, to control the flow of the paint 95 through the same, and thus regulate the width of the line made by the instrument.

100 The devices for controlling the air-blasts are constructed as follows: The bar or lever E', to the forward end of which the operating-lever E is pivoted, is itself pivoted at e between two lugs e' e' , fastened to the interior of the case. The arm of the lever E', remote from that to which the operating-lever E is pivoted, is provided with an uprising 105 portion e^2 , which is provided with an overhanging arm e^3 . The said overhanging arm e^3 is located over the perforation b' made in the nipple b and rests upon a part of the rubber tube b³ adjacent to said perforation. E² indicates 110 a spring secured at one end to the case and having its other end arranged to bear upon the overhanging arm e^3 to firmly hold the same in contact with the rubber tube, so as to close the said perforation in the nipple, and thereby prevent the passage of air. It will 115 be obvious that by pressing downwardly upon the operating-lever E the overhanging arm e^3 will be raised against the action of the spring 120

E² from contact with the rubber tube, so that the air which is maintained under pressure by a suitable air-forcing pump will lift the adjacent part of the rubber tube and will be 5 free to escape outwardly through the nozzle for the purpose described.

It follows from the above construction that the operating-lever or thumb-piece E performs two functions—that is to say, by presenting the same downwardly the air-blast is started, and then by either advancing or retracting said operating-lever the nibs or paint-conducting points will be separated or brought together, so as to regulate the quantity of paint 15 which will be acted upon by the air-blast.

I claim as my invention—

1. A paint-distributer comprising a paint-receptacle having a yielding portion, a perforation in said yielding portion, two nibs secured to the exterior of said receptacle and on either side of said perforation, means for bending said yielding portion, whereby the nibs are separated or brought together, and an air-blast nozzle adjacent to said nibs, substantially as described.

2. A paint-distributer comprising a paint-receptacle having a resilient yielding portion, a perforation in said resilient yielding portion, two nibs secured to the exterior of said receptacle and on either side of said perforation, means for depressing the said resilient yielding portion of the paint-receptacle, whereby the nibs are brought together, and an air-blast nozzle adjacent to said nibs, substantially as described.

3. A paint-distributer comprising a paint-receptacle having a resilient yielding portion, a perforation in said resilient yielding portion, two nibs secured to the exterior of said paint-receptacle and on either side of said perforation, an arm adapted to bear against and depress the said resilient yielding portion of the said paint-receptacle, whereby the nibs are brought together, and an air-blast nozzle adjacent to said nibs, substantially as described.

4. A paint-distributer comprising a paint-receptacle having a resilient yielding portion, a perforation in said resilient yielding portion, two nibs secured to the exterior of said receptacle and on either side of said perforation, a pivoted arm having one end adapted

to bear against the said resilient yielding portion, an operating-lever arranged for contact with the other end of said arm and adapted to swing the latter on its pivot and to depress said resilient portion, and an air-blast nozzle adjacent to said nibs, substantially as described.

5. A paint-distributer comprising a paint-receptacle having a resilient yielding portion, a perforation in said resilient yielding portion, two nibs secured to the exterior of said paint-receptacle and on either side of said perforation, a pivoted lever, as D, having one arm adapted to bear against the said resilient yielding portion and the other arm having an inclined edge, a swinging lever, as E, located adjacent to said inclined edge and adapted to impinge against the same and to swing the lever D on its pivot, and an air-blast nozzle adjacent to said nibs, substantially as described.

6. A paint-distributer comprising a paint-receptacle having a resilient yielding portion, a perforation in said resilient yielding portion, two nibs secured to the exterior of said paint-receptacle on either side of said perforation, a pivoted lever, as D, having one arm adapted to bear against the said resilient portion and the other arm having an inclined edge, a swinging operating-lever, as E, located adjacent to said inclined edge and adapted to impinge against the same, a guide located in contact on the other side of said operating-lever, and an air-blast nozzle adjacent to said nibs, substantially as described.

7. A paint-distributer comprising a paint-receptacle having a resilient yielding portion, a perforation in said resilient yielding portion, two nibs secured to the exterior of said receptacle on either side of said perforation, an air-blast nozzle located adjacent to said nibs, a valve in said air-blast nozzle, and an operating-lever connected with said resilient yielding portion and with the said valve, substantially as described.

In testimony that I claim the foregoing as my invention I affix my signature in presence of two witnesses.

CHARLES L. BURDICK.
